UNITED STATES PATENT OFFICE.

HERMANN LEMP, OF LYNN, MASSACHUSETTS, ASSIGNOR TO GENERAL ELECTRIC COMPANY, A CORPORATION OF NEW YORK.

MOTION-CHECKING DEVICE FOR WHEEL STEERING MECHANISMS.

No. 833,280.

Specification of Letters Patent.

Patented Oct. 16, 1906.

Application filed May 19, 1905. Serial No. 261,144.

To all whom it may concern:

Be it known that I, HERMANN LEMP, a citizen of the United States, residing at Lynn, county of Essex, State of Massachusetts, have 5 invented certain new and useful Improvements in Motion-Checking Devices for Wheel Steering Mechanism, of which the following is a specification.

This invention relates to automobiles having steering-gear operated by a hand-wheel; and its object is to provide a simple and effective hydraulic check for the same.

In a pending application, Serial No. 188,848, I have shown and claimed broadly 15 a steering-gear in which there is a power-multiplying device between the hand-wheel and the steering-wheels and a hydraulic checking device independent of or separate from the power-multiplying device. The 20 present application relates to a specific form of such a structure in which the checking is performed by two pistons connected to a rocker and working in separate cylinders connected by a passage controlled by a balanced valve, which reduces to a minimum the 25 effort required to operate it.

The invention is especially applicable to high-speed cars, where all lost motion between the hand-wheel and the steering-wheels 30 must be eliminated in order to give the operator perfect control. For this reason those forms of steering-check which require an initial movement of the steering handle or wheel to open the valves before the 35 steering-gear is actuated are unsuitable for high-speed cars. In the present invention there is no lost motion due to the steering-check. The checking is performed by pistons acting on a body of liquid, and the 40 strains are transmitted to them by short straight connections, so that the parts are rigid and immoveable when the valve is closed. The check is controlled by a single balanced valve whose movement is not effected by the pressure of the liquid. Its 45 line of motion is perpendicular to the plane of rotation of the hand-wheel, so that the slight effort required to operate it does not affect the accuracy of the steering. The 50 valve is preferably operated by squeezing together two adjacent hand-wheels at the upper end of the steering-post, one wheel being secured to the steering-post and the other wheel connected with the valve.

In the accompanying drawings, Figure 1 is 55 a sectional elevation of an inclined wheel-steering gear equipped with my improved motion-checking device. Fig. 2 is a similar view of the cylinders, pistons, and valve. Fig. 3 is an elevation of the lower portion of 60 the device looking from the opposite side of Fig. 1. Fig. 4 is a front view of the parts shown in Fig. 3. Fig. 5 is a cross-section on the line 5 5, Fig. 2. Fig. 6 is a cross-section on the line 6 6, Fig. 1. Figs. 7 and 9 are sectional elevations of a hand-wheel, illustrating 65 modifications. Figs. 8 and 10 are respectively plan views of the same; and Figs. 11, 12, 13, and 14 are details of construction of 70 said wheels.

The casing 1 is provided with a flange 2 for securing it to the floor of the automobile-body, the axis of said casing being inclined at any desired angle to said floor. The cap or bonnet 3 of said casing is bolted to said 75 flanges and is provided with upwardly-extending arms 4, supporting a bearing 5 for the steering-post 6, to whose upper end is secured the hand-wheel 7. Between the arms 4 is a bevel-pinion 8, secured to the lower end 80 of the steering-post and meshing with a segment bevel-gear 9, mounted on one of the trunnions 10 of a rocker or walking-beam 11, located inside the casing 1. Said trunnions are journaled in the casing and the bonnet 3. 85 The opposite trunnion carries an arm 12, which actuates the steering-wheels of the vehicle. A guard 13 is preferably secured to the side of the bearing 5 and overlaps the segment-gear to keep it in mesh with the 90 pinion.

Pivoted to each end of the rocker 11 is a connecting-rod 14, which is also pivotally attached to a trunk-piston 15. The two pistons operate in suitable cylinders 16, 95 formed in the casing 1, each piston having proper cup-packing 17 to make it fit watertight in its cylinder. The axes of the cylinders are preferably parallel with the axis of the steering-post. Between the cylinders is 100 a valve-chamber 18, connected by ports 19 20 with said cylinders. The chamber is preferably cylindrical and is provided with a bushing 21. A tubular valve 22 is located in said chamber, having heads 23, which have 105 a sliding fit in said bushing. The port 19 from one cylinder communicates with the space between the heads 23 and by moving

the valve upward said space can also be put into communication with the port 20, thereby connecting the two cylinders. Normally the valve stands as shown in Fig. 1, closing the port 20. As the two heads 23 present the same area, the pressure on them in the space between them is balanced.

The casing is filled with liquid, such as oil, which passes through the tubular valve to the lower end of the valve-chamber, thus balancing the pressures on the ends of the valves. The valve and its bushing can be readily removed, when necessary, by taking out the screw-plug 24 in the bottom of the casing.

In order to operate the valve, there is provided a rod 25, attached to its upper end and passing up through the casing, the rocker, and the steering-post. The rocker has a slot 26 to permit it to oscillate without striking the rod. A helical spring 27 surrounds the rod and slots between the valve and a stationary disk 28, resting against the heels of the rocker. Said spring tends to keep the valve normally closed. The upper end of the rod is attached to some manual operating device by means of which the operator of the car can manipulate said valve. In Fig. 1 this consists of a wheel 29, located under the hand-wheel 7 and of the same size, the adjacent faces of the rims being preferably flattened so that the two rims 30 31 form portions of a cylindrical ring. The spokes of the wheel 29 project through slots in the hub of the wheel 7, and the hub of said wheel 29 is fastened to the upper end of the rod 25. By grasping both rims and squeezing them together the operator will lift the rod and open the valve.

In driving a high-speed car it is usual for the operator to hold himself firmly against the top of the hand-wheel. If the wheel resists the turning effort, it is natural for the operator to grasp the rim more tightly. Now with the construction shown the tighter the rim is grasped the wider the valve is opened. It might even be desirable to adjust the valve so that it will never close completely, but will permit the wheel to be moved slowly. Then on high-speed work, where very little motion is required and where it is of the utmost importance to have as little loose play as possible, the car could be steered without pressing the rims at all. Squeezing the rims would only be necessary when a decided change in direction was wanted, and this action would be performed almost automatically without any great mental effort on the part of the operator. I have shown, however, two modifications in which the rim is not divided and is free to rotate through a limited angle, the lost motion being utilized to open the valve. Figs. 7, 8, 11, 12 show the rod 25, passing up through the top of the steering-post and se-

cured to a sleeve or hub 32, having spokes 33, which carry the inverted-V-shaped cams 34. The hand-wheel 35 is loose on the post and is provided with studs or antifriction-rollers 36, engaging the under side of said cams. An arm 37 is rigidly secured to the post and has clamped to it a yoke 38, which moves with one of the spokes 33, but permits a spoke 39 of the hand-wheel to have some lateral play therein. When the hand-wheel is turned, this lost motion causes the rollers 36 to lift the cams 34 and with them the valve-rod. When the hand-wheel has moved far enough to fully open the valve, its spoke 39 strikes one side of the yoke and turns the steering-post. The weight of the rod 25 and the valve, aided by the spring 27, restores the parts to their normal position when the hand-wheel is brought to rest in any angular position, thereby locking the steering-gear in such position.

Figs. 9, 10, 13, 14 show another modification in which the hand-wheel 40 is secured to the rod and is lifted by its cams 41 when rotated. The arms 37, carrying the rollers 36, are secured to the steering-post, and one of them has the yoke 38 secured to it, one spoke 42 of the hand-wheel having a certain amount of lost motion in said yoke. There is a slight disadvantage in this construction in that the operator may unconsciously lift the wheel by pulling on it and so unlock the steering-gear, so that I prefer the other forms shown.

The operation of the device may be briefly recapitulated, as follows: When the valve is closed, the pistons cannot move, and consequently the rocker is locked, the segment-gear is immovable, and the steering-wheels cannot alter their position. When the valve is opened, the steering-post can be rotated, because the liquid can flow from one cylinder to the other, permitting the rocker to be oscillated by the pinion and segment-gear, which at the same time move the arm 12, connected to the steering-wheels of the car.

It will be observed that the whole device is strong and compact, the casing for the checking device serving as the support for the steering-post, and the pistons moving in lines parallel with the axis of said post. This construction saves considerable valuable space in the car and effects a saving in weight.

What I claim as new, and desire to secure by Letters Patent of the United States, is—

1. In a steering mechanism for vehicles, the combination with a steering-post and hand-wheel, of a pinion on said post, a segment-gear meshing with said pinion, a hydraulic checking device controlling said gear, a valve mechanism for the hydraulic checking device, a valve-actuating rod carried by the steering-post, and a handle on said rod

- adjacent to the rim of said hand-wheel, so that both can be conveniently grasped by the hand of the operator.
2. In a steering mechanism for vehicles, the combination of a hydraulic checking device, a steering-post, a longitudinally-movable rod carried by said post, a steering hand-wheel on said post, and a hand-wheel on said rod adjacent to the steering hand-wheel.
3. In a steering mechanism for vehicles, the combination with a steering-post and hand-wheel, of a hydraulic checking device, a valve mechanism therefor, and means whereby the degree of opening of the valve depends upon the grasp of the operator's hand on said hand-wheel.
4. In a steering-check, the combination with a rocking element, of pistons attached thereto, cylinders for said pistons, and a valve controlling a passage-way between said cylinders.
5. In a steering mechanism for vehicles, the combination with a steering-post, of a rocking element oscillated by said post, pistons actuated in opposite directions by said rocking element, cylinders for said pistons, a valve controlling a passage-way between said cylinders, and a rod attached to said valve and carried by said post.
6. In a steering mechanism for vehicles, the combination with a steering-post, of a hydraulic checking device comprising two pistons movable simultaneously in opposite directions, cylinders for said pistons, a valve controlling the flow of liquid from one cylinder to the other, and a valve-rod carried by said post.
7. In a steering mechanism for vehicles, the combination with a steering-post, of a hydraulic checking device comprising two pistons moved in opposite directions when said post is turned, cylinders for said pistons and a balanced valve controlling a passage-way between said cylinders.
8. In a steering mechanism for vehicles, the combination with a steering-post, of a hydraulic checking device comprising two cylinders, a valve-chamber between them, a piston in each cylinder connected with said post, a balanced valve in said chamber, a spring for closing said valve, and a rod for opening it carried by said post.
9. In a steering-check, a casing having two cylinders, a valve-chamber between them communicating with both, a tubular valve in said chamber having heads of equal area exposed to the hydraulic pressure, and pistons in said cylinders.
10. In a steering-check, a casing having two cylinders, a valve-chamber between them communicating with both, a tubular valve in said chamber having heads of equal area exposed to the hydraulic pressure, pistons in said cylinders, and a rocker connected with said pistons.
11. In a steering-check, a casing having two cylinders, a valve-chamber between them communicating with both, a tubular valve in said chamber having heads of equal area exposed to the hydraulic pressure, pistons in said cylinders, a slotted rocker connected with said pistons, and a valve-rod passing through said slot.
12. In a steering mechanism for vehicles, the combination with a casing containing cylinders and a valve-chamber, of a bonnet for said casing carrying a bearing, and a steering-post rotatable in said bearing.
13. In a steering mechanism for vehicles, the combination with a casing containing cylinders and a valve-chamber, of a bonnet for said casing carrying a bearing, and a steering-post rotatable in said bearing in line with said valve-chamber.
14. In a steering mechanism for vehicles, the combination with a casing and a bonnet therefor, of a rocker having trunnions journaled in said casing and bonnet, a segment-gear on one trunnion, and a steering-arm on the other.
15. In a steering mechanism for vehicles, the combination with a casing and a bonnet therefor, of a rocker having trunnions journaled in said casing and bonnet, a segment-gear on one trunnion, a steering-arm on the other, and a steering-post supported on the bonnet and carrying a pinion meshing with the segment-gear.
16. In a steering mechanism for vehicles, the combination with a steering-post, of a hydraulic checking device comprising a piston movable in a line parallel with the axis of said post.
17. In a steering mechanism for vehicles, the combination with a steering-post, of a hydraulic checking device comprising two pistons movable simultaneously in opposite directions in lines parallel with the axis of said post.

In witness whereof I have hereunto set my hand this 17th day of May, 1905.

HERMANN LEMP.
